UNITED STATES PATENT OFFICE.

JAMES R. STULL, OF KANSAS CITY, MISSOURI.

DESIGN FOR A SOAP-BUBLER.

51,488.

Specification for Design.

Patented Nov. 13, 1917.

Application filed August 18, 1917. Serial No. 187,029. Term of patent 3½ years.

To all whom it may concern:

Be it known that I, JAMES R. STULL, a citizen of the United States, residing at Kansas City, in the county of Jackson and State of Missouri, have invented a new, original, and ornamental Design for Soap-Bubblers, of which the following is a specification, reference being had to the accompanying drawing, forming part thereof.

The figure is a perspective view of a soap bubbler, showing my new design.

I claim:

The ornamental design for a soap bubbler, as shown.

JAMES R. STULL.
